UNITED STATES PATENT OFFICE.

JAMES W. JORDAN, OF WILLIAMSBURG, KENTUCKY.

DUST-EXCLUDER.

1,298,347.

Specification of Letters Patent. Patented Mar. 25, 1919.

Application filed February 8, 1918. Serial No. 216,048.

To all whom it may concern:

Be it known that I, JAMES W. JORDAN, a citizen of the United States, residing at Williamsburg, in the county of Whitley and

5 State of Kentucky, have invented a new and useful Dust-Excluder, of which the following is a specification.

This invention relates to a dust excluder of that class intended to be worn as a covering for the nose and mouth to protect the same from dust and dirt.

10 The main object of the invention is to provide a protector of this character which may be easily and readily adjusted and removed.

A further object is the provision of a simple, durable and efficient dust excluder.

15 With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed can be made within the scope of what is claimed without departing from the spirit of the invention.

A practical embodiment of the invention 30 is shown in the accompanying drawing, wherein:—

Figure 1 is a perspective view of the device applied;

Fig. 2 is a central vertical section through 35 the same.

In carrying out the invention there is provided a frame 1 of irregular elliptical for-

mation and preferably constructed of wire, to which is secured by soldering or otherwise the forwardly extending arched member or support 2 the rearwardly extending 40 ends of which merge into the bent or hooked portions 3 which are adapted to take over the ears of the user of the device for the purpose of retaining the device in place.

Gauze 4 is secured to the frame 1 and supported by the support 2 and, covering the nose and mouth of the wearer, serves to exclude dirt and dust.

A device of this character is extremely useful in mills, factories, about threshing 50 machines and in any place where an excessive quantity of dust is continually in the air.

Having thus described the invention, what is claimed as new and sought by Letters 55 Patent, is:—

A device of the class described, comprising an arch member embodying in a one-piece structure, a forwardly extended bend and rearwardly extended ear engaging 60 arms; a loop-shaped frame secured at its sides and intermediate its ends to the arch member at the rear of the bend; and a covering peripherally assembled with the loop-shaped frame and supported by the bend.

65 In testimony that I claim the foregoing as my own, I have hereto affixed my signature in the presence of two witnesses.

JAMES W. JORDAN.

Witnesses:

I. N. STEELY,
E. L. STEPHENS.
